UNITED STATES PATENT OFFICE.

OTTO EMIL NEUMANN, OF NEW YORK, N. Y., ASSIGNOR OF ONE-HALF
TO THEODORE FRANK, OF BROOKLYN, NEW YORK.

SMOKE-CONSUMING FURNACE.

SPECIFICATION forming part of Letters Patent No. 779,176, dated January 3, 1905.

Application filed November 13, 1903. Renewed November 28, 1904. Serial No. 234,545.

To all whom it may concern:

Be it known that I, OTTO EMIL NEUMANN, a citizen of the Empire of Germany, residing in New York, in the borough of Brooklyn and 5 State of New York, have invented certain new and useful Improvements in Smoke-Consuming Furnaces, of which the following is a specification.

This invention relates to smoke-consuming furnaces, and has for its object to provide means whereby soft or bituminous coal or anthracite coal may be burned in such a manner as to consume all the coal particles in the smoke and whereby the fuel may be automatically fed to the grate in a regular and reliable manner, so as to keep up a uniform supply of fuel on the grate.

For this purpose the invention consists of a smoke-consuming furnace comprising a combustion-chamber, a grate in said combustion-chamber provided with a central opening, a fuel-receptacle, a chute for supplying fuel to said receptacle, and means for vertically reciprocating the receptacle for receiving the fuel from the chute, passing the receptacle up to the central opening of the grate, and for discharging the fuel onto the grate.

The invention consists, further, of an inclined grate, a second grate contacting there-with and inclined in opposite direction and provided with a central opening, and sliding gates below said opening for closing the same.

The invention consists, further, in rotating the grates so as to permit the convenient cleaning of the same of ashes and clinkers and in providing the combustion-chamber at its sides and top with double walls, respectively, for heating the feed-water and air and for commingling the latter with the products of combustion for insuring a perfect combustion of the same; and the invention consists, lastly, of certain details of construction and combinations of parts, which will be fully described hereinafter and finally pointed out in the 45 claims.

In the accompanying drawings, Figure 1 represents a front elevation of my improved smoke-consuming furnace. Fig. 2 is a verti-

cal longitudinal section of the same on line 2 2, Fig. 1. Fig. 3 is a vertical transverse section on line 3 3, Fig. 2. Fig. 4 is a horizontal section on line 4 4, Fig. 2, drawn on a smaller scale. Fig. 5 is a horizontal section on line 5 5, Fig. 2, also drawn on a smaller scale. Fig. 6 is a vertical central section of the fuel-receptacle and actuating means therefor when in position for being supplied with fuel. Fig. 7 is also a vertical central section of the fuel-receptacle and actuating means therefor when in position for discharging the fuel. Fig. 8 is a vertical longitudinal section of my improved smoke-consuming furnace shown as applied to a water-tube boiler. Fig. 9 is a horizontal section on line 9 9, Fig. 8; and Fig. 10 is a detail vertical center section 65 through the grate-supporting rotatable frame of the furnace shown in Fig. 8, drawn on a larger scale.

Similar letters of reference indicate corresponding parts.

Referring to the drawings, A represents a combustion-chamber provided at its sides with double walls *a* and having its top inclined and also provided with double walls *b*, suitably provided with a layer *c* of heat-insulating material, so as to prevent loss of heat by radiation. The combustion-chamber A is supported by standards *a'*, to which the grate D is attached, which is preferably circular in shape and provided with a central opening. 75 In the central opening of the grate D a second grate E, inclined in opposite direction to the grate D, is arranged. The grate E is supported by its angular lower end *e*, which forms a circular opening on standards F, attached at their lower ends to horizontal braces *f*. The braces *f* are suitably secured in the side walls of a well W, in which a fuel receptacle G and means for vertically reciprocating the same are arranged. The grates D 80 and E may be of circular, square, or other shape, according to the type of boiler with which my improved smoke-consuming furnace is used. Below the lower grate E sliding gates H are arranged, which are adapted to close 95 the central opening of the lower grate E, so

as to prevent any fuel from falling into the well. The gates H are provided at their lower sides with racks h, which are engaged by toothed segments I, supported by cam-shaped levers L, pivoted on shafts l, journaled in the standards F. The shafts l support casings l', in which spiral springs l² are arranged.

The fuel receptacle G is adapted to be vertically reciprocated by means of pistons P, movable in cylinders P', provided at their lower ends with openings P², adapted to communicate with openings m of valve-casings M, ways m¹⁰ of valves M¹⁰ receiving their motor medium from pipes m'. When the motor medium passes through the ways m¹⁰ of the supply-valves M¹⁰, through the openings m of the valve-casings M, and through the opening P² of the cylinder P', the pistons P ascend and move the fuel-receptacle G upwardly. Near the end of the stroke of the pistons the receptacle G encounters the cam-shaped levers L, supporting the segments I, which engage the racks h of the sliding gates H and cause the gates to be laterally moved apart so as to permit the fuel-receptacle G to pass up to the central opening of the lower grate E. When the fuel-receptacle reaches this position, openings n of a cylinder N, attached to the bottom 30 of the receptacle G, are brought in communication with an opening m² of the valve-casings M. The motor medium passing through the openings n into the cylinder N causes the piston N' in the cylinder N to be moved upwardly, whereby a platform O, attached to the upper end of the piston N', is also moved upwardly, so as to force the fuel in the receptacle G out of the same and onto the grate E. The fuel resting on the grate E is only 35 subjected to partial combustion, which causes the smoke produced to contain considerable quantities of carbon particles. This smoke passes over the burning fuel on the grate D, so that the carbon particles in the smoke are caused to be almost completely burned. The 40 partially-burned fuel on the grate E is, by a charge supplied by the fuel-receptacle G and platform O, moved over onto the grate D, where it is subjected to a considerable draft 45 and intense combustion.

To the platform O is attached a tube R, which passes through an opening g of the receptacle G and in which a second tube R' and a rod R², connected at its lower end with 55 the valves M¹⁰, are adapted to be telescopically folded. The tube R is provided with a slot r, running the full length of the same, in which lugs r' of the second tube R' move until 60 interposed by an adjustable nut T on the exterior of the tube R. The adjustable interiorly-screw-threaded nut T engages the exterior screw-threads of the outer tube R. The second tube R' is also provided with a slot r², running the full length of the same, in which 65 lugs r³ of the interior rod R² move until in-

terposed by the portion of the tube R' forming the end of the slot. By this arrangement the tubes R R' and rod R² form a telescopic joint, which is extended when the platform O is in its highest position and by the pull on 70 the same cause the valves M¹⁰ and casings M to be moved out of alinement with the opening p² of the cylinder P', whereby the motor medium in the cylinders P' passes out of the same and permits the pistons P to descend. 75 The openings m² of the casing M are of somewhat greater length than the openings m, so as to cause the motor medium to exert its pressure on the piston N' of the cylinder N for a longer time than on the pistons P, so as 80 to prevent the platform O from descending before the fuel-receptacle. In this manner the material is prevented from falling back into the receptacle. On the descent of the fuel-receptacle G the platform O and the cylinder N are caused to descend, whereby the openings n of the cylinder N are moved out of alinement with the openings m² of the casings M, and when the openings n are free of the casings M the motor medium passes out of the 85 cylinder N and permits the piston N' and the platform O to descend. However, before the platform O commences its descending movement the sliding gates H are caused to be closed by the action of the springs l² in the 90 casings l'. Hereby the fuel is prevented from being returned into the fuel-receptacle. When the fuel-receptacle G and cylinder N approach their lowermost positions, the receptacle is supplied with fuel from a chute C, 100 and lugs N² of the cylinder N engage a plate M³ of the valve-casings M and cause the same to be moved downwardly, so as to cause the openings m of the valve-casings M to be brought into communication with the openings P² of 105 the cylinder P', and so cause the motor medium to enter the cylinder P', move the piston P and fuel-receptacle G upwardly, and repeat the movements just described. The rods R² are screw-threaded at their lower ends and 110 provided with nuts R³, which are adjustable, so as to adjust the valves M¹⁰ in the valve-casings M. The nut T is vertically adjustable on the outer tube R, whereby the time of the actuation of the valve-casings M may be regulated. 115

In Figs. 8, 9, and 10 is shown the application of my improved grate to a water-tube boiler. In this case the outer grate D' is supported by inclined bars D² of a ring-shaped 120 frame D³, which is provided with a raceway D⁴, movable on balls D⁵ of a raceway D⁶ in a second ring-shaped frame D'. The upper ring-shaped frame D³ also supports a grate E² and is provided with a circumferential gear-wheel E³, which may be rotated from the outside of the furnace-walls by means of a suitable pinion and transmission means. To the lower ring-shaped frame D' is attached a wind-chest D⁹, supported by the standards F, square 130

at its lower end and round at its upper end. The wind-chest is provided with perforations H' and connected with supply-pipes H'', as shown clearly in Fig. 10. The wind-chest D' acts as a twyer, the draft-air passing through the perforations H'. By the rotation of the grates the grates may be readily cleaned of ashes and clinkers, inasmuch as all sides become accessible from the front and sides of the

10 furnace.

The double wall *a* of the combustion-chamber A forms a reservoir, to which feed-water is supplied by means of a pipe *v*, from which it is conducted off by a pipe *v'*. The upper 15 part of the combustion-chamber is preferably inclined and provided with an opening *b'* and a screen *b''*, through which air passes into the channel formed by the walls *b*, which air is heated and conducted by a channel V' and 20 branch channel V⁴, so as to commingle with the products of combustion of the furnace and cause the complete combustion of the remaining parts of carbon in the smoke passing over the bridge-wall V of the furnace. The channel V' is provided with a valve V², operated 25 by a handle V³, by means of which the heated air may pass through a side channel V⁵, so as to facilitate the cleaning of the same and drop the ashes into the ash-pit X of the furnace.

30 The advantages of my improved smoke-consuming apparatus are, first, the fuel is supplied to the grate in an automatic manner and distributed uniformly over the grate, so as to be subjected to uniform combustion; second, 35 carbon particles in the smoke are completely burned by the commingling of the heated air with the products of combustion; third, the ashes and clinkers may be easily removed from the grates, whereby the fire may be kept 40 in better condition. Moreover, my improved smoke-consuming furnace is simple of construction and effective in operation, being automatic in its action and not requiring skilled labor.

45 I claim as new and desire to secure by Letters Patent—

1. A smoke-consuming furnace, comprising an inclined grate provided with an opening, a second grate contacting with the walls forming the opening of the first grate inclined in opposite direction to the first and provided with an opening, sliding gates for said opening, fuel-conveying means passing up to said opening, and means actuated by said fuel-conveying means separating the gates from each other for opening the same and moving the

5 gates toward each other for closing the same, substantially as described.

2. A smoke-consuming furnace, comprising an inclined grate, a second grate inclined in opposite direction to the first and provided with an opening, gates for said opening, a well below said grates, a fuel-receptacle, means in the well for reciprocating the same, a platform in said fuel-receptacle, means for reciprocating the platform, and means actuated by said fuel-receptacle for opening or closing the gate, substantially as set forth. 60

3. A smoke-consuming furnace, comprising an inclined grate, a second grate inclined in opposite direction to the first and provided with an opening, gates for said opening, a fuel-receptacle, means for vertically reciprocating the same, a platform in said fuel-receptacle, means for vertically reciprocating the same, means actuated by the fuel-receptacle for opening or closing the gates, valves for said receptacle and platform reciprocating means, and means for actuating the valves at the end of the upper and lower reciprocation 75 of the platform, substantially as set forth.

4. A smoke-consuming furnace, comprising an inclined grate, a second grate inclined in opposite direction to the first and provided with an opening, gates for said opening, means 80 engaging said gates for opening or closing the same, a fuel-receptacle, a platform in said receptacle, an inclined chute for supplying fuel to said receptacle when in its lowest position, and means for reciprocating the receptacle and the 85 platform for delivering the fuel in the receptacle to the grates, substantially as set forth. 90

5. A smoke-consuming furnace, comprising a lower ring, an upper ring provided with a circumferential gear-wheel and rotatable on 95 said lower ring, an inclined grate supported by said upper ring, a second grate provided with an opening inclined in opposite direction to said first grate and also supported by the upper ring, gates for said opening, means for 100 opening or closing the same, means for supplying the grates with fuel, and means for rotating the gear-wheel of the upper ring for 105 rotating the grates, substantially as set forth.

In testimony that I claim the foregoing as my invention I have signed my name in presence of two subscribing witnesses.

OTTO EMIL NEUMANN.
